UNITED STATES PATENT OFFICE.

WILLIAM H. CASTLE, OF ASHTABULA, OHIO.

CAR-COUPING.

SPECIFICATION forming part of Letters Patent No. 280,449, dated July 3, 1883.

Application filed April 21, 1883. (No model.)

To all whom it may concern:

Be it known that I, WILLIAM H. CASTLE, a citizen of the United States, residing at Ashtabula, in the county of Ashtabula and State 5 of Ohio, have invented certain new and useful Improvements in Car-Couplings; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to car-couplings; and 15 the novelty consists in the construction and arrangement of parts, as will be more fully hereinafter set forth, and specifically pointed out in the claims.

The prime object of the invention is to provide 20 a car-coupling which shall be efficient in service, and at the same time cheap of manufacture, simple in operation, and not liable to get out of order; and to these ends the invention consists, essentially, in the mechanisms 25 fully illustrated in the accompanying drawings, which form a part of this specification, and in which—

Figure 1 is an end view of a car with my invention attached. Fig. 2 is a detail view of 30 one of my improved draw-heads broken. Fig. 3 is a detail section of one of the stirrups which support the draw-head; Fig. 4, a detail section of the locking parts; and Fig. 5 is a section of a detail, showing the manner and means for 35 holding the draw-heads against their gravity; Fig. 6, a section of the stirrup.

Referring to the drawings, in which similar 40 letters of reference indicate like parts in all the figures, A designates the body of an ordinary freight-car, and B one of its longitudinal timbers, or a plate rigidly secured upon its bottom. Secured to this part B is a frame, C, having a vertical perforated head, c, through the perforation in which operates loosely a bar, C', 45 having an eye in one end, in which is pivoted the draw-head F, and an annular flange, c', between which and the head c operates the stout spring D, which cushions the concussion arising from the cars coming together in coupling with the ordinary link-coupler, and hav-

ing also an annular flange, c², between which and the head c upon the other side operates the spring D, which cushions the jerk or pull of the car after the coupling has been accomplished.

The draw-head F is formed, essentially, of 55 two plates arranged one above the other, each formed in one piece with a solid head, said head having the ordinary aperture to receive the coupling-link x. The draw-head is suspended from the bottom and end of the car by means of stirrups G and chains g', the draw-head bearing upon friction-rollers g, journaled in the stirrups. Each draw-head has formed upon one or both of its sides an engaging-hook, 60 H, and the hook of each is adapted to engage the solid head of the other between the upper and lower plates. By this means the hook of 65 each draw-head has a vertical play equal to the whole distance between the upper and lower 70 plates of the draw-head less the thickness of the hook, and the strain is transferred from the hook to the solid part of the head, and when thus engaged the hooks are prevented from jumping out or uncoupling vertically by 75 means of the upper and lower plates of the draw-head. By means of a chain, I, secured at one end to the draw-head and at the other to a double-crank lever, I', journaled vertically in the end of the car, the draw-head may be 80 oscillated to uncouple when desired, as shown in dotted lines in Fig. 1. The journal or pivot J is at such distance from the face of the end 85 of the car that when the chain-crank has been turned sufficient to carry the plane of the chain I beyond the pivot the gravity of the draw-head will force said crank against the car, and thus hold the said draw-head locked until, by the manipulation of the lever I', the chain is again thrown outwardly past the pivot, when the 90 gravity of the draw-head will again throw it out into its full operative position.

What I consider to be elements of importance in this invention are the suspended oscillating draw-head, the means for locking it 95 out of operation by its gravity, the means for suspending it, and the construction of the head and hook.

Modifications in details of construction may be made without departing from the principle 100

or sacrificing the advantages of the invention, the essential features of which have been fully indicated.

My construction holds the link in position, preventing its swinging when coming in contact with link-couplers.

When my coupler is on both cars, only the back spring is required, the draw-heads passing by and the bumpers receiving the shock.

10 It is obvious that the coupler can be raised or lowered by hooking the chain nearer to or farther from the coupler.

The coupler can be operated from the side or top of car, and the position of the crank indicates whether the coupler is in position for coupling or not.

15 My coupler is especially adapted to couple and draw on a curve by having a free lateral movement.

20 Having thus fully described my invention, what I claim as new, and desire to secure by Letters Patent of the United States, is—

1. In a car-coupling, a draw-head having engaging-hook, and bearing upon friction-rollers in stirrups suspended by chains from the car-body, a chain and crank-lever for forcing

the draw-head out of operation, and means for automatically locking it against the action of its gravity, substantially as herein set forth,

2. The draw-head F, having hook H, as described, combined with the stirrups G, having friction-rollers g, the chains g', and the bar C', as set forth.

3. The suspended draw-heads F F, each formed with an upper and lower plate and a solid head, and having hook H, adapted to engage the solid head of the adjacent draw-head between the plates, whereby a vertical play is given to the coupling greater than the width of the hook, as set forth.

4. In combination with the suspended draw-head, chain I, and crank-lever I', the pivot-bracket J, placed distant from the face of the car, whereby the chain I may be thrown past the pivot to lock the draw-head out of operation, as herein specified.

In testimony whereof I affix my signature in presence of two witnesses.

WILLIAM H. CASTLE.
